ICE CREAM SCOOP

Monte Levin, Koslyn Heights, N.Y., assignor to Rudi Baer, doing business as Progressus Company, New York, N.Y.

Filed Aug. 30, 1966, Ser. No. 3,652

Term of patent 14 years

(Cl. D44—29)

I claim:

The ornamental design for an ice cream scoop, as shown.
